US00D727317S

(12) **United States Design Patent**
Olsson et al.

(10) **Patent No.:** **US D727,317 S**
(45) **Date of Patent:** **** Apr. 21, 2015**

(54) **WEARABLE DISPLAY DEVICE**

(71) Applicant: **Google Inc.**, Mountain View, CA (US)

(72) Inventors: **Maj Isabelle Olsson**, San Francisco, CA (US); **Mitchell Joseph Heinrich**, San Francisco, CA (US)

(73) Assignee: **Google Inc.**, Mountain View, CA (US)

(**) Term: **14 Years**

(21) Appl. No.: **29/450,536**

(22) Filed: **Mar. 19, 2013**

Related U.S. Application Data

(60) Continuation of application No. 29/430,738, filed on Aug. 29, 2012, now Pat. No. Des. 680,152, which is a continuation of application No. 29/418,739, filed on Apr. 20, 2012, now Pat. No. Des. 669,066, which is a division of application No. 29/404,654, filed on Oct. 24, 2011, now Pat. No. Des. 666,237.

(57) **CLAIM**

The ornamental design for a wearable display device, as shown and described.

DESCRIPTION

FIG. 1 is a front perspective view of a wearable display device according to a second embodiment of our design;

FIG. 2 is a front elevation view of the wearable display device of FIG. 1;

FIG. 3 is a back elevation view of the wearable display device of FIG. 1;

FIG. 4 is a right elevation view of the wearable display device of FIG. 1;

FIG. 5 is a left elevation view of the wearable display device of FIG. 1;

FIG. 6 is a top elevation view of the wearable display device of FIG. 1; and,

FIG. 7 is a bottom elevation view of the wearable display device of FIG. 1.

Broken lines are environmental only and form no part of the claimed design.

1 Claim, 5 Drawing Sheets
